Primary Examiner—Jeffrey Asch*(74) Attorney, Agent, or Firm*—Banner & Witcoff, Ltd.**CLAIM**

The ornamental design for a key button area for a handset, as shown and described.

DESCRIPTION

FIG. 1 is a front view of a key button area for a handset showing my new design; and,

FIG. 2 is a perspective front view thereof.

The broken line showing of portions of a handset in the figures is for illustrative purposes only and forms no part of the claimed design.
